UNITED STATES PATENT OFFICE.

JAMES J. MURPHY, OF DENVER, COLORADO.

EXTENSIBLE RULE AND PENCIL.

Application filed November 10, 1925. Serial No. 68,055.

This invention relates to a combination pencil and extensible rule.

Mechanics and others oftentimes find it necessary and very convenient to carry a rule which will enable them to determine distances either in the English scale of inches or in the metric scale. It is also frequently desirable to have a pencil where it can be readily found and used. Pencils of the type known as eversharp or which have a mechanism by means of which a molded piece of lead can be extruded so as to always provide a proper pencil point are quite extensively carried by the general public. It is very seldom, however, that any one carries about with him a rule of any kind. It is the object of this invention to construct a pencil in such a manner that it can be extended to a considerable length and to provide the same with graduations by means of which distances may be measured. This pencil is preferably formed of three telescopic members of a square cross-section, the smaller and innermost member forming the pencil proper and containing some suitable mechanism for controlling the extrusion of the lead.

The type of pencil which I intend to employ as the foundation for this rule is one in which by rotating a portion of the pencil, the lead can be extended to any desired distance.

In order to describe my invention so that its construction can be readily understood, I shall have reference to the accompanying drawing in which the preferred embodiment thereof has been illustrated and in which:

Figure 1 shows my combined pencil and rule extended to full length;

Fig. 2 shows the same in collapsed form with a portion broken away to better disclose the construction; and

Fig. 3 is a section taken on line 3-3, Fig. 1, showing the manner of connecting the sections to one another.

My extensible rule consists of three sections, A, B, and C. The section indicated by A is the pencil and is formed from a square piece of tubing within whose interior is housed the mechanism for controlling the lead. As any suitable mechanism may be employed for this purpose, I have not gone into details in explaining the means by which the lead is controlled as this is a separate invention from the combination

described herein. One end of section A has a conical portion which has been indicated by numeral 1 and extending radially from this is a knurled flange 2, which can be grasped for the purpose of rotating the parts and of extruding the lead 3. Slidably on the tubular member 4 of section A is a similar tubular member 5 whose interior dimensions are slightly larger than the exterior dimensions of the part 4, and connected to part 5 of section B is a similar square tubular section 6, whose interior dimensions are slightly greater than the exterior dimensions of the part 5. In order to prevent the several parts from being separated one from the other, I secure to the outer ends of parts 4 and 5 a ferrule 7 and to the inner parts of sections 5 and 6 a similar ferrule 8. These abut each other when the rule is extended to its utmost length and prevents the parts from being separated. When the parts are collapsed they also serve to keep them from wobbling with respect to each other. In order to produce the necessary friction to hold the parts in adjusted position, I preferably slit the ends of parts 4 and 5 in the manner indicated by line 9 in Fig. 3. This makes the end resilient and serves to press the outside of the ferrule 7 against the interior of the surrounding tube. One side of this extensible scale is provided with graduations in inches and fractions of an inch in the manner indicated on the right-hand side of the perspective view shown in Fig. 1. The other side shown on the left-hand side of the perspective view in Fig. 1 is divided into parts representing centimeters or some multiple or decimal thereof, so that the two scales are always available either for the English system or the metric system. The other two sides of the parts 4, 5, and 6 are left blank and it is the intention to apply to these sides some suitable advertising matter, as it is for this purpose as well as for the convenience of the combination that this invention is intended.

It will be noted that the base of the conical portion 1 has a diameter somewhat greater than the diagonal dimension of the section A whereby a shoulder D is formed which serves as a stop for the sections B and C when they are moved towards closed position.

When the parts are collapsed they have the appearance shown in Fig. 2 and have

a size substantially corresponding to that of an ordinary pencil of this type.

In order to prevent the pencil from becoming lost and to attach it to the pocket, I have provided a clip 10 that is adapted to receive between it and the side of the pencil a portion of the pocket so as to prevent its accidental removal.

The knurled flange 2, aside from its function in enabling the lead to be regulated, also serves as a handle for the purpose of extending the several parts. If the conical end had a perfectly smooth exterior surface, it is evident that more or less difficulty would be experienced in pulling the parts out into extended form; whereas, with this annular ridge, a good grasp can be had of the pencil section while the section 6 can be firmly held by the fingers of the other hand.

Having now described my invention, what I claim as new is:

1. A combined pencil and measuring rule comprising, in combination, three telescopic sections of rectangular cross-section, the

smallest of which has a conical point provided with an axial opening for the reception of a lead, said conical portion having an annular flange adapted to be grasped when moving the parts from collapsed to extended position, the larger end of said conical portion having a shoulder adapted to serve as a stop for the other sections when in collapsed relation.

2. In a combined pencil and measuring rule, in combination, a plurality of telescopic sections each formed from a rectangular tube, the smaller of said sections having a conical end provided with an axial opening for the reception of a lead, the larger end of said conical portion having a shoulder that serves as a stop for the other sections when in collapsed position and having also an outwardly extending flange which serves as a grip for moving the parts from collapsed to extended position, one side being graduated in inches and the other in centimeters.

In testimony whereof I affix my signature.
JAMES J. MURPHY.
